UNITED STATES PATENT OFFICE.

JOSEPH PETER KOECHNER, OF TIPTON, MISSOURI.

AUTOMOBILE-JACK.

1,191,520.

Specification of Letters Patent. Patented July 18, 1916.

Application filed April 5, 1916. Serial No. 89,024.

To all whom it may concern:

Be it known that I, JOSEPH P. KOECHNER, a citizen of the United States, residing at Tipton, in the county of Moniteau and State 5 of Missouri, have invented certain new and useful Improvements in Automobile-Jacks, of which the following is a specification.

This invention relates to improvements in automobile jacks and one of its objects is to 10 produce a jack particularly adapted to use in public garages and it contemplates the provision of a jack that is adjustable to fit automobiles of different sizes and which may have axles of various lengths.

15 Another object is to produce a jack that is cheap to manufacture and efficient in operation and that will allow for the automatic raising of one end of the vehicle by simply running the vehicle over the apparatus.

20 With the foregoing and other objects in view the invention consists in the combination and arrangement of parts to be herein-after fully described in the following specification and illustrated in the accompanying drawings which form a part of said specification and in which—

Figure 1 is a plan view of my improved automobile jack. Fig. 2 is a rear end view 30 of the same. Fig. 3 is a side elevation showing a machine being moved into engagement with the jack. Fig. 4 is a similar view showing the machine engaged by the jack. Fig. 5 is a longitudinal sectional view 35 taken on line 5—5 of Fig. 1. Fig. 6 is a fragmentary detail view. Fig. 7 is a section taken on line 7—7 of Fig. 6. Fig. 8 is a fragmentary view showing the connection of one of the standards and the frame of the 40 jack. Fig. 9 is a section taken on line 9—9 of Fig. 8.

Like reference characters denote corresponding parts throughout the several views.

The reference numeral 1 denotes a base 45 block formed with transversely extending grooves 3, 3 which serve as guides for the bolts 4 carried by angle pieces 5, 5 which are secured to the longitudinal brace beams 6, 6 that run parallel with the sides 7, 7 of the 50 jack frame and that are connected thereto by the pivot bolts 8, 8 and by the bolts 9, 9, said latter bolts also connecting the oblique frame ends 10, 10 to the sides 7 and beams 6 which latter members are spaced away from 55 each other throughout their length as shown. At one end the said sides 7 and beams 6 rest

upon a lower sectional cross beam 11, 12, each beam-section being apertured as at 13 and covered by a piece of metal plate 14 formed with an elongated slot 15 through 60 which the connecting bolts 16 extend that lock the beam-sections in adjusted relation. An upper sectional cross beam 17, 18, of identically the same construction as the beam 11, 12 is provided with the locking 65 bolts 19 to secure its sections fixedly in adjusted relation. A transverse brace beam of like sectional formation and designated by the numerals 20, 21 is provided with the locking bolts 22 to permit its adjustment as 70 desired; said beams 17, 18 and 20, 21 serving as stops for the standards 23 to be herein-after described.

Upon the aforesaid pivot bolts 8 the standards 23 are arranged, said standards 75 being formed with a plurality of bolt-receiving perforations 24 to permit their adjustment with relation to the frame members 6, 7 to accommodate automobiles having wheels of various diameters. It is readily 80 seen the jack frame can be adjusted in a horizontal plane by means of the cross beams that carry the beams 6, 6 and sides 7, 7; one beam 6 together with one side 7 being jointly adjustable with relation to the remaining 85 beam and side 6 and 7; this adjustment having been above described. When the frame is set to accommodate an automobile the machine is run over the jack until one of its axles rides into engagement with the concave cut portion 25 of the standards when 90 the standards will be moved, upon their pivotal supports, from the position shown in Fig. 3 to the position shown in Fig. 4 thus raising one end of the machine off the 95 ground and taking its weight entirely off the wheels of the raised axle.

I wish it understood that the invention is not to be confined strictly to the constructive arrangements shown, but may include a 100 number of variations, so long as the essential character of the invention is not modified.

What is claimed is:

1. In an automobile jack, a base block, a 105 lower adjustable cross beam, a frame formed of relatively adjustable frame-sides connecting said base block and adjustable cross beam, and standards pivotally arranged in said frame-sides.

2. In an automobile jack, a base block, a 110 lower adjustable cross beam, a frame formed

of relatively adjustable frame-sides connecting said base block and adjustable cross beam, standards pivotally arranged in said frame-sides, and upper adjustable cross beams connecting the said frame-side and serving as stops for the said standards.

3. In an automobile jack, a grooved base block, a lower adjustable cross beam, a frame formed of relatively adjustable frame-sides connecting said base block and adjustable cross beam, angle pieces carried by said frame-sides, bolts carried by said angle pieces and slidably disposed in the grooved

portions of said base block, standards pivotally arranged in said frame-sides, and means 15 adjustably connecting said frame-sides whereby the pivotal movement of said standards is limited.

In testimony that I claim the foregoing as my own I have hereto affixed my signature 20 in the presence of two subscribing witnesses.

JOSEPH PETER KOECHNER.

Witnesses:

JOSEPH VOGEL,
CHARLES J. ORESCHELER.
